UNITED STATES PATENT OFFICE.

WILLIAM J. KELLY, OF CLINTON, IOWA.

SUPPORTING DEVICE.

1,257,611.

Specification of Letters Patent. Patented Feb. 26, 1918.

Application filed February 29, 1916. Serial No. 81,106.

To all whom it may concern:

Be it known that I, WILLIAM J. KELLY, a citizen of the United States, residing at Clinton, in the county of Clinton and State 5 of Iowa, have invented a new and useful Improvement in Supporting Devices, of which the following is a specification.

My invention relates, more particularly to devices for supporting mattresses, or the like 10 articles, preferably for the housing and displaying of the same in vertical position.

My primary object is to provide a simple and effective construction of clamp to engage the upper edge of the mattress for supporting it in depending position, without injuring the mattress, and preferably to permit the mattresses to be moved relative to each other to display condition and with equal facility replaced in the rack.

Referring to the accompanying drawings:—

Figure 1 is a view in front elevation of a rack equipped with a plurality of my improved supporting devices, showing the rack 25 partly filled with mattresses. Fig. 2 is a view in side elevation of the upper portion of the rack. Fig. 3 is a section taken at the line 3 on Fig. 1 and viewed in the direction of the arrow, one of the mattresses being extended in the rack to display condition. Fig. 4 is a view in front elevation of one 30 of the similar guide-tracks employed. Fig. 5 is a section taken at the line 5 on Fig. 3 and viewed in the direction of the arrow. Fig. 6 is a view in side elevation of my 35 improved mattress-clamp showing it in closed position. Fig. 7 is a bottom plan view of the clamp. Fig. 8 is a perspective view of the clamp in open condition; and Fig. 9, a front view of a portion of the rack 40 showing one of the tracks and with a clamp (shown in part only) engaging the guide.

In the particular construction illustrated, wherein provision is made for permitting 45 any of the mattresses to be moved substantially parallel with the others thereof to project it beyond the others, and for use in connection with which feature I have more particularly devised my invention, the rack 50 is made of bars of angle-shape assembled and secured together to form a rectangular structure. At the front and back portions of the rack the bars are positioned to form rectangular frames, as shown of the front 55 portion of the rack in Fig. 1, these bars being represented at 10, 11, 12 and 13. The

rectangular frames thus provided are connected together in spaced relation at their upper and lower corners by cross-bars at opposite sides of these rectangles connected 60 with the bars of the latter as represented of the upper cross-bars indicated at 14, to form the rectangular rack, braces 16 being provided at the corners of the rack, except across the front thereof, which is left open. 65 The rack thus provided is of a height and depth somewhat greater than the height and width of the mattresses to be housed therein and of a width to permit as many of the mattresses as desired being housed therein. 70

Secured at their ends against the undersides of the upper bars 10 are guide-tracks 17, which are spaced apart in parallel relation and extend from the rear of the rack to a point slightly in front of the front side 75 of the rack, as represented in Figs. 2 and 3. These guide-tracks, preferably constructed of metal, are each of general inverted U-shape in cross-section with inwardly-extending flanges 18 projecting from the opposed 80 edges thereof and terminating in upturned sections 19 spaced apart to form a slot 20, bolts 21 passing through the sides of the guide-tracks at intervals to prevent spreading.

The guide-tracks 17 are provided for receiving and supporting the devices from which the mattresses, as, for example, those illustrated at 22, are suspended, and forming guides along which these devices may 90 slide to project portions of the mattresses through the front of the rack beyond the front edges of the other mattresses to display the mattresses as desired.

The particular form of mattress-supporting device illustrated, and which is the form in which I prefer to provide my invention, is formed of side bars 23 and 24 of angle-iron and of a greater length than the width of the mattress to be supported; the bar 24 100 being rigidly connected at one end with a bar 25 and pivotally connected at its opposite end with a bar 26 having a notch 27 in its inner edge, the opposite end of the bar 25 being pivotally connected at 28 with the adjacent end of the bar 23, which latter is equipped at its opposite end with a pin 29 adapted to enter the notch 27 when the clamping device is in closed position, the flanges of the bars 23 and 24 being preferably extended inwardly toward each other, as represented, and the arrangement of the

parts just described being such that when the clamp is closed about the end of a mattress, as hereinafter explained, the flanges just referred to will compress the mattress sufficiently to sustain it in suspended position. The clamp is provided at its end adjacent the bar 25, and intermediate its ends with yoke-shaped hangers 30; each formed of angle-shaped sections 31 and 32 pivoted together at upwardly-deflected sections 33 and 34 thereon, as represented at 35, the sections 31 being rigidly connected with the bars 24 to extend upwardly therefrom at an angle and the sections 32 containing notches 36 in their edges for engagement with pins 37 on the bar 23 when the clamp is closed. The upper ends of the sections 33 are equipped with short shafts 38 extending beyond opposite sides of these sections and 20 equipped at their projecting ends with rollers 39.

In use the clamps are secured about the ends of the mattresses to be suspended thereby, by positioning them in open condition 25 (Fig. 8) over the end-portion of the mattresses a slight distance from the extremities of the latter. The bars 23 are then forced toward the side of the mattresses to firmly grip the latter between the bars 23 and 24. 30 The bars 26 are then interlocked at their notches 27 with the pins 29 by swinging the bars 26 on their pivots and the sections 32 then swung toward the respective pins 37 to interlock the notches 36 with these pins. 35 The mattresses, with the clamps applied as stated, are then introduced into the rack to the position shown in Fig. 1, the rollers 39 entering the channels 17^a provided by shaping the guide-tracks as stated, and supporting 40 the mattresses from the latter. When it is desired to display one of the mattresses the operator grasps its forward edge and pulls it forwardly, the clamping device from which it is supported rolling along the track 45 on its rollers 39, the forward ones of which preferably engage a removable and replaceable stop-device, shown as a cotter-pin 40 secured in the side-walls of the track, as represented in Fig. 3, wherein one of the mattresses is shown in extended, display condition, it being understood that when desired the mattress may be returned to its original position in the rack by pushing it back to place, the roller-engagement of the clamp- 55 ing-device, with the tracks, permitting of the ready manipulation of the mattresses into and out of display position.

While I have illustrated and described a particular embodiment of my invention, I 60 do not wish to be understood as limiting it thereto, as the same may be variously modified and altered without departing from the spirit of my invention. Furthermore, while I have shown my improved device in connection with an apparatus in which the mat-

tresses are supported in a particular relation and are movable relative to each other in a certain way, I do not wish to be understood as intending to limit my invention to use in such connection, as certain features there- 70 of are useful, wherein the mattresses, or other articles, are supported to extend otherwise and also be movable otherwise, where supported to be moved relative to each other to display position.

75

What I claim as new and desire to secure by Letters Patent is—

1. A mattress-clamp comprising side-bars, end-bars connected with one of said side-bars, one of said end-bars being pivotally connected thereto, the other of said side-bars being relatively movable toward and away from the first-mentioned side-bar to permit the clamp to be opened, and means on said pivotal end-bar and said last-referred-to 85 side-bar to releasably hold said side-bars against movement away from each other, for maintaining the clamp in closed position about a mattress.

2. In a mattress-clamp, the combination 90 of bars adapted to be spread apart to render the clamp open for receiving a mattress, and a hanger formed of relatively movable rigid upwardly-extending sections carried by one of the bars and adapted at one of its 95 sections to releasably engage the opposite bar when the clamp is closed.

3. In a mattress-clamp, the combination 100 of bars adapted to be spread apart to render the clamp open for receiving a mattress, and a hanger of yoke-shape with its arms pivotally connected together, one of its arms being connected with one of the side-bars and its other arm provided with means for 105 engaging the opposite side-bar when the clamp is in closed position.

4. A mattress-clamp comprising side-bars and end-bars, certain of said bars being pivoted together, said bars adapting the clamp to be opened and closed, and a hanger, 110 formed of relatively movable sections, connected with one of said side-bars and adapted to releasably engage the other side-bar when said clamp is closed.

5. A mattress-clamp, comprising side-bars 115 and end-bars, certain of said bars being pivoted together, said bars adapting the clamp to be opened and closed, and a hanger of yoke-shape with its arms pivotally connected together, one of its arms being connected 120 with one of the side-bars and its other arm provided with means for engaging the opposite side-bar when the clamp is in closed position.

6. A mattress-clamp comprising side-bars 125 and end-bars, certain of said bars being pivoted together, said bars adapting the clamp to be opened and closed, a hanger of yoke-shape with its arms pivotally connected together, the axis of the pivot connecting said 130

- arms extending transversely of said side-bars, one of the arms of said hanger being connected with one of the side-bars, and means formed of coöperating elements on 5 the other arm of said hanger and the opposite side-bar, adapted to engage each other upon swinging said last-referred-to arm on its pivot when said clamp is closed, for holding the clamp in closed position.
- 16 7. In a mattress-clamp, the combination of bars adapted to be spread apart to render the clamp open for receiving a mattress, a hanger formed of pivotally connected sections, one of which is connected with one 15 bar, the pivot of said hanger extending transversely of said bars, and means formed of coöperating elements on the other section of said hanger and the opposite bar adapted to engage each other upon swinging said 20 last-referred-to arm on its pivot when said clamp is closed, for holding the clamp in closed position.
8. A mattress-clamp comprising side-bars
- and end-bars certain of said bars being pivoted together, said bars adapting the clamp 25 to be opened and closed, a hanger of yoke-shape with its arms pivotally connected together, the axis of the pivot, connecting said arms, extending transversely of said side-bars in a plane substantially parallel 30 with the plane in which the side bars are movable in opening and closing the clamp, the arms of said hanger being rigid, with one of said arms connected with one of the side-bars and the other arm being movable 35 at its pivotal connection into and out of a position in which it overlaps the opposite side-bar, and means on said last-referred-to arm and said last-referred-to side-bar for releasably connecting these bars together 40 when the clamp is in closed position.

WILLIAM J. KELLY.
